BURIAL VAULT LOWERING DEVICE

Charles W. Goodsman, Portland, Oreg., assignor
to Frigid Fluid Company, a corporation of
Illinois

Application November 19, 1932, Serial No. 643,455

4 Claims. (Cl. 254—136)

This invention relates to lowering apparatus adapted particularly for use in lowering a heavy burial vault into a grave.

The primary object of the invention is to provide a simple mechanism which can be taken apart without difficulty after being used and will occupy but a small space. The device may be assembled by comparatively unskilled workmen but will work satisfactorily without requiring any fine adjustment or particular care in assembling. A further object of the invention is to provide a lowering device which is made up in two units disposed at opposite ends of the grave and cooperate in lowering a vault although each end is individually controlled by an operator.

The invention is illustrated in a preferred embodiment in the accompanying drawings, in which—

Fig. 1 is a plan view of the improved apparatus supporting a burial vault, the base of which supports a casket and is ready to receive the lid of the vault which is shown on conveying wheels at the left; Fig. 2 is an end elevational view of a grave over which the lowering device and accompanying mechanism have been positioned to lower a lid of the vault into position; Fig. 3 is a side elevational view showing one of the conveying devices in engagement with the lid of a burial vault; Fig. 4 is a plan view of one part of one of the end frames of the mechanism; Fig. 5 is a broken plan sectional view of the same from below; Fig. 6 is an end elevational view taken as indicated at line 6—6 of Fig. 4; Fig. 7 is a sectional view taken as indicated at line 7—7 of Fig. 4; and Fig. 8 is a sectional view taken at line 8—8 of Fig. 4.

In the embodiment illustrated, 1 designates a grave having shoulder portions 2 and 3 which support the vault lowering device. The device is disposed around the marginal portion of the grave with the winding mechanisms at each end upon which is placed a vault base 4. The vault base may be placed in position before a funeral party arrives to place a casket 5 thereon. A vault lid 6 may then be moved into position so as to cover the casket and rest on the vault base which will then be ready for lowering into the grave. Preferably a pair of wooden blocks are provided at the bottom of the grave to support the assembly 50 and permit the supporting cables to be swung out from under the ends of the vault. This avoids the necessity for unfastening one end of the cable or providing it with a releasable connection. Preferably track members 7 and 8, which may 55 be in the form of wooden planks, are provided to

facilitate movement of the vault, on conveyor wheels 9 and 10, to position over the grave. The end frames which are equipped with winding mechanism have supporting brackets 52 and 53 which fit over the track members 7 and 8 and by beveling their upper edge portions as shown in Fig. 6, the conveying wheels will roll over the same without difficulty. The track members 7 and 8 serve to hold the end frames in proper spaced relation and also prevent the pulley supports, described below, from causing said frames to roll over.

The end frames are equipped with supporting shoes 54 and 55 which rest well back on the shoulders 2 and 3 of the grave.

Rigidly connected to the supporting brackets 52 and 53 are winding cases or housings 56 and 57. As the four mechanisms are similar we will describe but one in particular. Referring to Fig. 5, it will be seen that a hollow shaft 58 from the 20 companion mechanism of the same end frame makes a telescopic connection with shaft 59. Said shafts are provided with holes 60 so that they will make an adjustable driving connection with each other by use of a locking pin 61. A 25 winding drum 62 having a helical cable groove 63 is splined to the shaft 59 so as to be longitudinally movable thereon. A flexible connection 64, which may be a wire cable, chain, or the like, has its end portion 65 connected to said drum. In 30 order that the cable will always feed out of the same portion of the housing a cap screw 66 is provided in the housing and has a finger 67 which projects into the groove 63 and serves to move the drum longitudinally of the shaft 59 in timed 35 relation to the rotation thereof. As shown in Figs. 4—7, a hollow trunnion 68 supports a sheave 69, equipped with a hood 70 and a shaft 71. The trunnion 68 has a circumferential groove 72 which is engaged by a locking pin 73 screwed into the pulley-supporting boss 74 provided on the housing 57. Thus it will be understood that the cable extends through the trunnion 68 around the pulley 71 to the pulley in the companion winding mechanism. When the cable is wound up to receive the vault base, the pulleys will be in substantially a horizontal position as shown in Fig. 5. As the vault is lowered the pulleys will pivot on the trunnions 68 to the position shown in Figs. 6 and 7.

After the vault has been lowered and the loops in the cables swung from under the vault the device may be wound up by rotating the shafts 58 and 59 by means of gear 75 and worm 76, shown in Fig. 5. The shaft 59 is journaled in a pair 55

After the vault has been lowered and the loops in the cables swung from under the vault the device may be wound up by rotating the shafts 58 and 59 by means of gear 75 and worm 76, shown in Fig. 5. The shaft 59 is journaled in a pair 55

of closure heads 77 and 78 which make a threaded connection with the housing. As shown in Figs. 4 and 6 the end of the worm shaft is equipped with a nut 79 so that the shaft may be rotated easily by means of a crank.

In rolling a vault lid over the grave it is desirable to have the front end tilted upwardly as shown in Fig. 3. In order to stop the forward movement of the vault at the proper position a stop member 80 having an upwardly projecting finger 81 is provided on the housing 57. The stop member may be provided with a ring clasp 82 having a finger 84 to engage the projection 83 in the housing to prevent the member from being swung below a horizontal position.

By using the conveying mechanism shown in Figs. 1-3, in connection with the lowering device, a very simple method of completely assembling the vault within the grave may be practiced. Usually, the vault has a base portion 4 and box-shaped cover 6, although in some cases the base is in the form of a box and a cover completes the closure. In either case, the conveying wheels 9 and 10 may be used to position the base 4 upon the lowering cables 64 before the funeral party arrives. The pall-bearers may then place the casket upon the base of the vault and the base and casket can be lowered until the top of the casket is at about the ground level. The conveying wheels may then be used to carry the cover over the base without raising the cover any higher than shown in Figs. 2 and 3. The base and casket may then be raised into engagement with the cover member by the manual rotation of the worm gears 76 at each end of the grave; or, if desired, the top may be lowered down to the base by means of the jack-screws provided in the conveying wheels. The conveying wheels can then be disconnected and the vault which has been sealed at the ground level may then be lowered into the grave, as will be readily understood.

The foregoing detailed description has been given for clearness of understanding only, and no unnecessary limitations should be understood therefrom, but the appended claims should be construed as broadly as permissible, in view of the prior art.

I claim:

1. In a lowering device: an end frame comprising two similar parts, each part comprising a housing, a shaft journalled in said housing, a cable drum splined to said shaft, means for mov-

ing the drum longitudinally of the shaft in timed relation to the rotation thereof, and a pulley rotatably and swivelly journalled on said housing adjacent to said cable drum; an adjustable driving connection between the ends of the shafts of the two parts; means for rotating said shafts; and a cable threaded through said pulleys and connected to said drums so as to be wound or unwound at both ends simultaneously when the shafts are rotated.

2. A mechanism as specified in claim 1, in which the cable drums are equipped with spirally wound grooves, one drum being wound to the right and the other to the left, and the means for moving the drum longitudinally of the shaft comprises stationary fingers mounted in the frame member so as to engage said grooves.

3. A vault lowering device comprising: a pair of end-frame members adapted to be disposed at opposite ends of a grave, each of said frame members having a shaft journalled therein, winding drums mounted on said shafts, a pair of pulley-supporting bosses on each of said end-frame members adjacent to said drums, a pulley rotatably and swivelly mounted on each of said bosses, a separate cable for each end-frame threaded over the pulleys thereof and attached at its ends to the adjacent drums; and a pair of side frame members adjustably secured to said end frame members to hold the same in longitudinal spaced relation and prevent rotation thereof while a vault is supported on said cables.

4. A vault lowering device comprising: an end frame adapted to be disposed at an end of a grave, said end frame having two similar parts and each part comprising a drum housing, a shaft journalled therein, a winding drum in said housing splined to said shaft, said drum being provided with a helical cable groove, stationary finger-means in said housing engaging said groove so as to move said drum longitudinally on the shaft in timed relation to the rotation thereof, and a pulley swivelly and rotatably mounted on said housing; a cable threaded over the pulleys of both parts and connected to the drums thereof; an adjustable driving connection between said shafts of the two parts; and manual means for simultaneously winding the cable on said drums.

CHARLES W. GOODSMAN.
